UNITED STATES PATENT OFFICE.

HENRY RAWAK, OF NEW YORK, N. Y.

DESIGN FOR A SCARF.

SPECIFICATION forming part of Design No. 18,454, dated July 10, 1888.

Application filed May 16, 1888. Serial No. 274,081. Term of patent 7 years.

To all whom it may concern:

Be it known that I, HENRY RAWAK, of the city, county, and State of New York, have invented a new and original Design for a Scarf, of which the following is a specification.

5 The object of the invention is to provide a new and original design for a scarf which is specially intended for political campaign purposes.

10 The invention consists of a scarf of contrasting colors and having two medallions for containing portraits on its upper or head part. The colors of the upper or head part of the scarf are arranged transversely, and in the

lower part of the scarf the said colors are arranged lengthwise. Upon the central transverse stripe of the head are arranged the medallions, as shown.

I claim—

15 The design herein shown and described, consisting of a scarf of contrasting colors and having on a central transverse stripe of its head two medallions.

HENRY RAWAK.
